UNITED STATES PATENT OFFICE.

CONSTANTINE KUZAROFF, OF ST. PAUL, MINNESOTA, ASSIGNOR OF ONE-HALF TO JOHN DERDOSKI, OF ST. PAUL, MINNESOTA.

DESIGN FOR A SMOKER'S TRAY.

Application filed June 19, 1925. Serial No. 13,818. Term of patent 3½ years.

To all whom it may concern:

Be it known that I, CONSTANTINE KUZAROFF, a citizen of the United States, residing at St. Paul, in the county of Ramsey and State of Minnesota, have invented a new, original, and ornamental Design for Smokers' Trays, of which the following is a specification, reference being had to the accompanying drawing, forming part thereof.

In the drawings:

The figure is a view in perspective of a smoker's tray embodying the design of the present invention.

I claim:

The ornamental design for a smoker's tray substantially as shown.

CONSTANTINE KUZAROFF.
